Ferdinand German Triay, Galashiels, England

Application May 29, 1943, Serial No. 110,323
In Great Britain April 30, 1943

Term of patent 7 years

(Cl. D34—5)

To all whom it may concern:

Be it known that I, Ferdinand German Triay, a British subject residing at Newholm, Tweed Road, Galashiels, North Britain, have invented a new, original, and ornamental Design for a Game Board, of which the following is a specification, reference being had to the accompanying drawing, forming part thereof.

The figure is a plan view of a game board, showing my new design.

The article is of conventional thickness.

I claim:

The ornamental design for a game board, as shown and described.

FERDINAND GERMAN TRIAY.
